UNITED STATES PATENT OFFICE.

JOSEPH LEONARD, OF NEW YORK, N. Y., ASSIGNOR TO FIFTH AVENUE CORSET COMPANY, INC., OF ALLENTOWN, PENNSYLVANIA, A CORPORATION OF NEW YORK.

HOSE SUPPORTER.

Application filed September 18, 1918. Serial No. 254,538.

To all whom it may concern:

Be it known that I, JOSEPH LEONARD, a citizen of the United States of America, and a resident of the borough of the Bronx, city 5 of New York, county of the Bronx, and State of New York, have invented certain new and useful Improvements in Hose Supporters, of which the following is a specification.

10 This invention has been designed particularly for supporting hose from corsets, but is applicable in connection with garments generally irrespective of the source of support or the garment which is supported. One object is to provide a substitute for elastic webbing, the elastic element of which is rubber, scarcity of which makes it increasingly difficult to obtain. Another object is to provide an elastic element which 15 will not deteriorate through the influence of the warmth and moisture of the body and continued strain, or more rapidly than the corset or other parts with which it is associated.

20 25 In the accompanying sheet of drawings which forms a part of this application—

Figure 1 is a perspective of a corset hose-supporter which embodies this invention,

Fig. 2 is a top view of the elastic element, 30 Fig. 3 is a section through the elastic element on the line III—III of Fig. 2, and

Fig. 4 is a section through the elastic element on the line IV—IV of Fig. 3.

A means of attachment 5 to the hose or 35 other supported garment of any suitable form has a pulley 6 connected therewith which may be in the form of a roller which turns on the wire frame of the attaching device. The elastic element comprises two 40 helical compression springs 7, 7 which are enclosed in slotted spring-barrels 8, 8. A first crossbar 9 has enlarged ends which project through the slots into the barrels and bear on the upper ends of each of the 45 springs. A second crossbar 10 connects the upper ends of the spring barrels, and the barrels, the lower ends of which are closed, serve as abutments for the lower ends of each of the springs. A bar 11 may connect 50 the lower ends of the barrels, if desired, to better hold them in place, but this is not es-

sential. A supporting tape 12 hangs from the lower edge of a corset 13, but it is not essential that it should be supported from the body in this manner. The tape is 55 branched. One branch 14 leads down behind the metal spring barrels, thereby keeping them from touching the wearer, and thence the branch is led around the pulley and up to the first crossbar to which the end is attached. The other branch 15 has its end attached to the second crossbar.

By reason of the pulley action the strains on the branches attached to the elastic element are half of the strain on the hose supporter, and one-fourth on each of the two springs, so that the springs and their casings may be light and of much smaller diameter than it has been necessary to show them on account of the requirements of clear 70 illustration. The connecting bars are preferably narrower than the diameters of the spring barrels so that the elastic element will have a distributed bearing against the branch of the tape behind it, which will more 75 or less concave in conforming to the leg of the wearer.

The foregoing detailed description has been given for clearness of understanding and no undue limitation should be deduced 80 therefrom but the appended claim should be construed as broadly as permissible in view of the prior art.

What I claim, is—

In a garment-supporter, the combination 85 with an elastic element including a pair of cross bars arranged adjacent one end of the elastic element, and means resiliently urging the cross bars into close relation to each other, of a supporting tape having one end 90 returned and connected to one of the cross bars, the elastic element being positioned between the returned portion and the body portion of the tape, a branch carried by the tape beyond the returned portion and attached to the other cross bar, and a means of attachment to a garment supported in the bight of the returned tape portion.

Signed at New York, N. Y., this 17th day of September, 1918.

JOSEPH LEONARD.
